INTEGRATING MECHANISM

Jack F. Shannon, Euclid, Ohio, assignor to Bailey Meter Company, a corporation of Delaware

Application April 30, 1953, Serial No. 352,172

5 Claims. (Cl. 74—789)

This invention relates to improvements in mechanisms for the integration of variables, especially mechanisms for integrating variables with respect to time, and where such variables may be of a physical, chemical, electrical, hydraulic or other nature.

This invention also relates to driving means for the mechanism for integrating variables wherein the basic source of power for the driving mechanism is a fluid pressure.

This invention is specifically an improvement of that type of integrator disclosed and claimed in the patent to Gorrie 1,892,183. The Gorrie device was compared, in its specification, with integrators of the planimeter, or friction contact, type wherein the speed of operation of the register is varied in accordance with the value of the variable, while the operation of the register is continuous. Gorrie declared, on this basis, that it was known to obtain a total over any period of time, or integrate a variable with respect to time by periodic determination of the value of the variable, with a movement of the register being proportional to the value of the variable. Gorrie then suggested the value of the variable be determined at some point of time within the period or interval, and the magnitude of the increments of movement of the register be made of a time length which is the percentage of the time period proportional to the value of the variable.

The Gorrie type of integrator comprises an arrangement wherein predetermined time intervals are chosen and the driving means for the register operated at a constant speed but without the value of the variable at a particular instant during the time interval being the determining factor of the amount of actuation of the register during the time interval. Actually, the Gorrie type of integrator employs a system wherein the length of actuation of the register during each interval of time chosen is in accordance with the value of the variable at a particular instant during that time interval, modified by the value of the variable throughout the actuation. In general, this is accomplished by allowing the value of the variable to change during that time or through that part of the interval of time wherein the register is actuated.

In an application S. N. 285,736, filed May 2, 1952, by Jack F. Shannon and Randall C. Aberegg, now Patent 2,690,871, the problem of providing a consistent mode of starting the integrating portion of the cycle in the Gorrie type of integrator was met with a specific structure. The approach in this Shannon et al. application was novel and effective in providing the desired function. However, certain dimensional limitations in commercial embodiments of this inventive concept have caused the present applicant to seek other structural solutions to the basic problem.

It should be noted that the dominating structure of the Gorrie integrator is the toothed, escapement wheel which is engaged by the pawl positioned by cooperation between the meter mechanism and the constant-rise cam driven by the constant-speed source of power for the

integrator. If the pawl must be engaged with the wheel teeth so positively that the disengaging force exerted by the pin positioned by the meter mechanism flexes, or bends, the pawl arm in forcing the disengagement, a "snap" of this pawl will take place. The sudden movement of the pawl arm will "jar" the positioned pin and be transmitted back to the recording mechanism, causing a disrupted record, and the pawl will "creep" up the successively engaged teeth, independently of the value of the variable the mechanism is attempting to integrate. The basic problem will be appreciated, therefore, as one of reducing the torque on this escapement wheel so that its engagement will be confined solely to the influence of the variable integrated.

Both the Gorrie patent and the Shannon et al. application disclosure make it clear that their source of constant speed is inherently arranged to drive the integrator register through a friction clutch which must be adjusted to meet the highest power requirements for turning the register mechanism. The mechanical arresting mechanism including the escapement wheel is very simple. The wheel is carried directly on the register shaft so that when engaged by the pawl the register is stopped. But the friction clutch between the source of constant speed and the register shaft then develops the undesirably high torque directly on the escapement wheel.

The Shannon et al. application disclosed a relief pawl which functioned during the interval of escapement wheel arrestment to reverse the rotation of the wheel a consistent, predetermined amount so the main pawl could swing free of its engaged tooth and the integrating period could start from precisely the same point in rotation despite the high torque on the escapement wheel. Thus the torque on the escapement wheel was not reduced by the Shannon et al. mechanism, but its effect was overcome by an additional pawl.

The present invention is directed to the fundamental approach of torque reduction on the escapement wheel structure of the Gorrie integrator. In general, the principle of mechanical gear differential structure has been utilized in the present invention to make the development of a high torque by the source of constant speed unnecessary. By control of a differential between the power shaft and register shaft with the escapement wheel, little more torque than the highest driving requirements of the register need be developed. This novel structure is adaptable to the Gorrie type of integrator as the addition of structure on the central shaft of the device takes less bulk than the provision of additional pivot points for structure such as the relief pawl of the Shannon et al. application.

Precisely the forms given the embodiments of the invention will be depicted in detail in the following description of the various drawing figures. The prime objective, of the invention, however, is the improvement of the Gorrie type of integrator by reduction of the power needed from the source of constant speed.

Other novelty in the disclosure of this application is found in the structure for supplying the source of constant speed. It is, of course, recognized that electric motors are the more conventional source of power for these mechanisms. However, there are some applications where the use of electric power is precluded because of safety measures. To provide for these applications, the present invention advances a unique, fluid-power mechanism which delivers sufficient power for the service required and at a constant rate. With the power requirements reduced, not only are relatively low-powered, fluid-actuated mechanisms feasible in this service, but spring-actuated mechanisms may be also satisfactory.

It should be appreciated that a start toward conception of this power mechanism begins with some form of

fluid turbine. The present disclosure illustrates the use of an air nozzle against the impeller blades of a simple turbine which is geared to deliver sufficient power to operate the integrating mechanism. The uniqueness of this specific structure disclosed lies in the combination of this fluid turbine, gears and a mechanism for metering the power available to the integrating mechanism at a constant rate.

Broadly speaking, the present invention provides structure for imposing the influence of an escapement mechanism on the gear train between the fluid turbine and the input shaft of the integrating mechanism. This structure is centered about a spring member attached to a shaft of the gear train and loaded from the escapement mechanism in order to provide a regulation of the force transmitted to the integrator.

It may now be appreciated that another object of the invention is to provide an improved fluid pressure mechanism for maintaining a source of constant speed for the working shaft of a mechanism absorbing or transmitting that power.

Another object of the invention is to provide a differential drive for the escapement type of integrator which is compact, easily manufactured, requires substantially no maintenance and improves the accuracy of the integration.

In the drawings:

Fig. 1 is an isometric and diagrammatic representation, with partial explosion, of the invention in connection with an escapement type of integrator responsive to a variable.

Fig. 2 shows a partially cross-sectioned side elevation of the invention of Fig. 1.

Fig. 3 shows a partially cross-sectioned side elevation of another form of the invention disclosed at Fig. 1.

Fig. 4 shows a partially cross-sectioned side elevation of another form of the invention disclosed at Fig. 1.

The disclosure of the drawings covers a complete integrating mechanism as driven by a source of power at a constant rate. The driving means, or source of power, has a novel arrangement of structure which will be subsequently described. However, as the ultimate function of the source of power is well established, the disclosure will be basically directed to the structural novelty of the escapement mechanism driving the register.

There are several variations of the escapement mechanism, all embodying the basic concept upon which patentable novelty depends. Present manufacturing techniques dictate the species which lends itself more readily to production. However, as manufacturing techniques change it is entirely possible that any one of the embodiments shown will be adopted by a specific manufacturer who takes advantage of this disclosure.

The species of the invention preferred for Figs. 1 and 2 was selected because of the clarity with which it lends itself to illustration. The alternate arrangements of Figs. 3 and 4 are easily understood, from an initial understanding of the arrangement of Figs. 1 and 2. Each of the arrangements of Figs. 3 and 4 may be substituted for that of Fig. 1 in combination with the source of power illustrated. Common numeral designations, on the characteristic cam and escapement wheel, have been used to emphasize this interchangeability, as well as the input and output gear members of this section of the combination.

The structure of the invention disclosed lends itself rather well to discussion in sections without impairing illustration of the unity and cooperation between the sections. I will first discuss the structure specifically designated by numerals 1-12 inclusive. A mechanism (not disclosed) is responsive to a quantitative variable to be integrated with respect to time to determine the total, or cumulative, quantity of the variable during a specific interval of time. What has been disclosed in Fig. 1 is a variable link 1 which is responsive to the undisclosed

mechanism. The variable link 1 will be caused to take up vertical positions over a range, indicative of the instantaneous value of the variable. To produce ultimately desired motions, variable link 1 is caused to rotate a variable link arm 2 which in turn rotates a shaft 3 in accordance with the variable. It is then possible to rigidly attach an indicating pointer 4 to shaft 3 and this pointer will then cooperate with exhibiting scale 5 for giving visual representation of the variable. A chart, moving with time, may be substituted for scale 5 and a recording pen may be substituted for pointer 4 to cooperate with the chart and give a permanent and continuous record with respect to time.

The indicating and/or recording of the variable magnitude, in this particular instance, is an incidental function of the disclosed structure. Fundamentally, the variably rotated shaft 3 has attached to it a pivot positioning beam 6 which carries variably positioned pivot 7 through an arc about the axis of shaft 3 over the normal range of positions representative of the variable. The variable pivot 7 is at one end of an integrating pin beam 8 whose opposite end carries a roller 9 whose vertical position between two limits in space is determined by the main cam of the integrating mechanism. With one end of beam 8 positioned by the variable and the other end of beam 8 positioned in accordance with a predetermined program, integrating pin 10, carried at an intermediate point on the beam 8, is caused to actuate pawl 11 about pawl pivot 12 for periodic engagement of the escapement wheel of the integrator and so regulate the actuation of the register which exhibits the quantitative total, or integration, of the variable.

The disclosure of this structure 1-12 would have its complete function clarified to some degree if the limits of movement in space were delineated for variable pivot 7 and integrating pin beam roller 9. However, a rather exhaustive analysis of these relative motions was made in the Gorrie Patent 1,892,183 and is not necessary here for an understanding of the present invention. Also, it is to be understood that in a practical reduction to practice of this structure, provision will be made for giving relative adjustments of integrating pin 10 on integrating pin beam 8 as well as adjustments to the position in space of pawl pivot 12. These adjustments are necessary for purposes of calibration but would be rather incidental disclosure here.

The structure disclosed thus far cooperates to engage the escapement wheel of the integrator with pawl 11 for periods representative of the value of the variable integrated. In general, a register with graduated dials, for affording a continuously available means of reading the accumulated total of the variable for a desired time interval is controlled by rotation of the escapement wheel. Actuation of this register is accomplished, through the novel arrangement of the present invention, from the mechanism of the integrator whose escapement wheel is controlled by engagement with pawl 11.

As the escapement wheel and/or cam is to be rotated at a constant speed, it is now well to turn to structure provided for giving this rotation. Here, again, a group of structures of the present disclosure may be considered as a unit without obscuring the cooperation with the remainder of the disclosed structure.

Beginning with the impeller turbine 20, it is easily understood how a blast of fluid from nozzle 21 will impinge upon the vanes of turbine 20 and rotate the turbine shaft 22. All of the gears and shafts of this structure 20-34 inclusive have been depicted diagrammatically without detracting from the clarity of the function of the structure.

On turbine shaft 22 there is mounted turbine shaft gear 23 which is one end of a train of gears mounted on shafts 24 and 25. Output shaft gear 26 represents the end of this gear train and it is from this output shaft gear 26 that power is delivered to the integrating mechanism

controlled by the escapement wheel 28. Of course there are design considerations involved which may call for additional intermediate shafts such as depicted by 24 with gears in the train from gear 23 to gear 26. These considerations include the power available from turbine shaft 22 and required at output shaft gear 26.

The present invention has provided an escapement mechanism generally indicated at 27, which is characterized by a conventional escapement wheel 28 whose shaft 29 has a gear mounted thereon as one end of a train cooperating with other gears mounted on intermediate shafts represented by 30 and terminating with regulating gear 31. In common with similar escapement mechanism, the structure of 27 is arranged to control wheel 28 so that shaft 29 will turn at a predetermined rate.

Shaft 29 will not turn continuously because the escapement mechanism inherently interrupts the rotation in one direction. Nevertheless, the intermittent rotation in the one direction proceeds at an average rate held constant by the escapement mechanism 27.

The rotation of regulating gear 31 is in the same direction as that of shaft 25. However, whereas the rotation of shaft 25 is directly under the control of turbine 20, the rotation of regulating gear 31 is under the control of escapement mechanism 27. It is contemplated that variations will occur in the fluid supplied nozzle 21, impinging on the vanes of turbine 20. Consequently, if the available power from turbine 20 were elevated above the requirements at output shaft gear 26, it would be desirable to throttle this available power by regulating gear 31 so that fluctuations from turbine 20 would be isolated from output shaft gear 26.

The present invention provides a regulating shaft 32 on which regulating gear 31 is mounted and regulating spring housing 33 connected to output shaft 25 through regulating spring 34. Obviously, shaft 32 is tubular and output shaft 25 extends therethrough for connection with the inner end of the coil of spring 34. The outer end of spring 34 is simply attached to spring housing 33 and the differential between the power available from turbine 20 and that required at output shaft gear 26 is stored in spring 34.

This arrangement solves two basic problems. First it solves the problem of providing a regulated rotation of output shaft 25. Secondly, it solves the problem of preventing the intermittent action of the escapement mechanism 27 from being transmitted to output shaft 25. The rocking motion of escapement wheel 28, transmitted directly to shaft 32 is absorbed by the resiliency of spring 34.

A source of constant speed has now been provided for the structure, centering about the cam and escapement wheel of the integrator. The power from this source is available at output shaft gear 26 and is taken directly to the integrator cam 42 through input gear 40 mounted on cam shaft 41, both of which are diagrammatically depicted in Fig. 1. Cam 42 of the integrator is fixed to this shaft 41 in all of the various arrangements of the invention disclosed. However, shaft 41 may actuate a different structure of the invention, dependent upon which species is being considered. Integrator escapement wheel 43 also controls, and is actuated by, different arrangements in the various species disclosed, but whatever the arrangements otherwise, an output gear 44 is provided to drive shaft 45 of register 46. All of this structure 40-46 is common with the various species of the invention disclosed and may be taken as a common denominator to illustrate their basic interchangeability.

Taking cam 42, in its connection to shaft 41 as driven by input gear 40, its function can be disposed of by reference to the basic Gorrie patent. This cam 42 is shaped to give a rise and fall to roller 9 at a uniform rate between two predetermined limits in space. This function is a basic requirement for this type of integrator and need not be discussed in more detail.

Taking the arrangement of Fig. 1, specifically, it is to be understood that cam shaft 41 has been broken in order to give clear illustration to the driving mechanism between escapement wheel 43 and output gear 44. A spider plate 47 has been fixed to cam shaft 41 so that, in this embodiment of Fig. 1, cam 42 and spider plate 47 turn together.

Pinion gears 48 and 49 are now to be considered, as their connecting shaft 50 is carried by spider plate 47. Pinion gear 48 is directly meshed with a gear turned by escapement wheel 43 and may, therefore, be referred to as the escapement pinion. Pinion 49 is meshed directly with a gear carried on the same shaft as output gear 44 and may, therefore, be referred to as the output pinion. These pinion gears, connected by shaft 50, may rotate in the hole in spider plate 47 provided for shaft 50 as well as execute a planetary motion about the axis of rotation of spider plate 47. To provide a desired function at a certain period in the operation of these parts, a constant friction member 51 is provided on the shaft of output gear 44.

In order to prevent any confusion whatsoever as to the relationships of these structures 40-51, Fig. 2 has been provided as a partially cross-sectioned side elevation of this same structure depicted in perspective in Fig. 1. The operation of this structure centers about rotation of shaft 41. If the escapement wheel 43 is free of pawl 11, spider 47 will impart a planetary motion to pinion gears 48 and 49 about the axis of rotation of shaft 41 while constant friction means 51 will prevent rotation of output gear 44 and, consequently, actuation of register 46. In order to transmit power through a differential with pinion gears having rotation about an axis parallel with that about which they describe a planetary motion, the pinion gears must have a differential in size. The exact differential in size will depend upon the speed desired for escapement wheel 43 when released and the speed desired for register 46 when escapement wheel 43 is engaged by pawl 11.

As specifically disclosed in Figs. 1 and 2, when escapement wheel 43 is engaged by pawl 11, the peripheral speed of the gear teeth of escapement pinion 48 is to be noted as less than that of the gear teeth on output pinion gear 49. Therefore, the gears meshing with these pinions will rotate at differential speeds and actuate register 46. When pawl 11 does not engage escapement wheel 43 constant friction 51 will prevent any friction from the gears rotating the shaft of output gear 44, and output pinion gear 49 will be noted as having a speed of rotation greater than the gear attached to escapement wheel 43 which meshes with escapement pinion gear 48. Escapement wheel 43 will then be driven in a direction opposite to the rotation of spider plate 47.

Returning to the basic objective of the present invention, it must be appreciated that this arrangement reduces the torque on escapement wheel 43 as compared with the prior arrangements wherein a friction clutch directly connected the escapement wheel to the cam shaft. This driving of the escapement wheel 43 through the differential dominated by pinion gears 48 and 49 in spider 47 eliminates the necessity of providing power equal to the highest register requirement plus that necessary to overcome the friction coupling between the source of constant rotation and the escapement wheel in the Gorrie type of integrator. The results obtain the objective of the invention in that, with the torque greatly reduced on escapement wheel 43, the disengagement from the teeth thereof by pawl 11 gives no disturbing reaction back through the linkage to a manifesting member such as pointer 4. Engagement and disengagement of the pawl 11 from the teeth of escapement wheel 43 follows more precisely the change of the variable because of the elimination of the disturbance due to the high torque on the escapement wheel.

Going now to Fig. 3, it must be initially appreciated

that this arrangement is based about the establishment of a fixed, central shaft 60. Input gear 40, cam shaft 41, cam 42, escapement wheel 43 and output gear 44 have the same basic identity and function as in the preceding figures. However, cam shaft 41 is now tubular and arranged to rotate about stationary shaft 60 under the control of input gear 40. Although tubular shaft 41 also carries cam 42 it does not now carry a spider as in the first two figures but terminates in a beveled gear in the differential structure. Output gear 44 is now provided with a tubular shaft 61 which rotates about stationary shaft 60 and extends back into the differential to connect with a spider plate 62 in which rotates the pinion gears 63 and 64. The escapement wheel 43 is also provided with a tubular shaft which accommodates output shaft 61 in order to extend a gear 65 back into the differential. The cam shaft gear 66, the two pinion gears 63 and 64 and the escapement gear 65 comprise the differential, with spider plate 62 having a fixed friction member 67 applied thereto after the fashion of member 51 in the preceding disclosure.

The cooperation of this structure of Fig. 3 is basically the same as the preceding disclosure in obtaining the improved results of the invention. Arrestment of escapement wheel 43 will cause cam shaft gear 66 to both rotate and impart a planetary motion to pinion gears 63 and 64 against the constant friction member 67, to drive spider plate 62 and attached output shaft 61 in actuation of register 46. It is again emphasized that the force needed to arrest escapement wheel 43 is relatively small compared to the prior arrangements wherein the escapement wheel was connected through a friction clutch directly to cam shaft 41.

When escapement wheel 43 is released from engagement with pawl 11, friction member 67 prevents rotation of spider plate 62 and pinion gears 63 and 64 merely rotate in transmitting the power from cam shaft gear 66 to escapement gear 65.

Going now to Fig. 4, the common denominator of structure between this figure and that of the foregoing disclosure, particularly Fig. 3, is easily located. Stationary shaft 60 is arranged as in Fig. 3, with cam shaft 41 and output shaft 61 arranged to slip over and turn on shaft 60. Cam 42, escapement wheel 43, as well as input gear 40 and output gear 44, are exactly as delineated in all of the foregoing disclosure. The central distinction between Fig. 4 and the foregoing figures lies in the attachment of escapement wheel 43 to the differential gearing through the agency of the pinion gear 81, which may be referred to as an idler gear in this particular arrangement.

Escapement wheel 43 has a shaft member 80 attached thereto which revolves about stationary shaft 60 and between cam shaft 41 and output shaft 61. This escapement wheel shaft 80 supports pinion gear 81 a spaced distance from the center of rotation in order that a gear on output shaft 61 may be meshed between gear 81 and stationary shaft 60. Meshed with the teeth of gear 81 a greater distance from shaft 60 are the teeth of a gear carried by cam shaft 41. It might be said that the three gears form their differential by meshing in a plane normal to their axis of rotation about stationary shaft 60. The accommodation on cam shaft 41 for its gear and the form given to escapement wheel shaft 80 are a little difficult to follow, but sufficient sectioning has been taken through this view of Fig. 4 to show the cooperation of the various components.

The constant friction device 82 has a function common with that of 51 and 67 in the preceding figures. Essentially, this device is to exert a constant, frictional drag on output shaft 61. In Fig. 4 this device is included on the shaft and exerts its friction on stationary shaft 60. In the preceding Fig. 3, the friction was seemingly easier to apply to the spider plate 62. However, the function of this device is the prevention of rotation by output gear

44, from the friction of the differential, when escapement wheel 43 is released from engagement with pawl 11.

The function of the structure of Fig. 4 should now be obvious, because of familiarity with the preceding disclosure. With escapement wheel 43 immobilized, the peripheral speed of the gear carried by cam shaft 41 is greater, about the axis of stationary shaft 60, than the speed of the gear on output shaft 61. It is this difference in speeds of the two gears meshed by pinion gear 81 which causes a transmission of power from shaft 41 to shaft 61. Of course the direction of rotation of the shafts are opposite. As in the preceding disclosure, the fundamental objective of the invention in reduction of torque on escapement wheel 43 is carried out as before.

What I claim as new and desire to secure by Letters Patent of the United States, is:

1. In an integrator including an escapement type of movement and having a register driven thereby, the combination comprising a stationary shaft, a tubular cam shaft rotating on one end portion of the stationary shaft, an external gear on the tubular cam shaft for rotating the same, the inner end of the tubular cam shaft being enlarged to provide an open-ended cylindrical housing formation provided with gear teeth on its inner periphery and having an operating plate cam extending outwardly thereof, a tubular output shaft mounted on the other end portion of the stationary shaft and having an enlarged inner end sleeve portion extending within said internal gear teeth in spaced relation thereto and to the stationary shaft and provided with external gear teeth in opposed spaced relation to said inner periphery gear teeth, a pinion gear in operating relation between said inner periphery gear teeth and said external gear teeth, a sleeve flanged at one end and rotatably mounted on the stationary shaft, means for periodically locking and releasing said sleeve for predetermined increments of time, a stub shaft mounted in perpendicular relation on the flanged portion of the last-mentioned sleeve and rotatably supporting the pinion gear, and an output gear on the other end of said tubular output shaft.

2. The combination of claim 1 in which a friction device is interposed between the tubular output shaft and the stationary shaft to exert a frictional drag on the last-mentioned shaft.

3. In an integrator including an escapement type of movement and having a register driven thereby, the combination comprising a stationary shaft, a first tubular shaft rotating on one end portion of the stationary shaft and having an external input gear fixed on the outer end thereof and a pinion gear fixed on the inner end thereof, a second tubular shaft rotating on the other end portion of the stationary shaft and having an external output gear fixed on the outer end thereof, an escapement wheel formed with an inwardly extending sleeve portion terminating in a pinion gear and rotatably mounted on the second tubular shaft, means for periodically locking and releasing said escapement wheel for predetermined increments of time, an annular spider plate encircling the said pinion gears, and a pinion gear rotatably mounted on the inner periphery of said spider plate meshing with the other two pinion gears.

4. In an integrator including an escapement type of movement and having a register driven thereby, the combination comprising a stationary shaft, a first tubular shaft rotating on one end portion of the stationary shaft and having an external input gear fixed thereon, a second tubular shaft rotating on the other end portion of the stationary shaft and having an external output gear fixed thereon, a differential gear train including a pinion gear interposed in engaged relation between a spaced pair of opposed gears, one of which is on the first tubular shaft and the other of which is on the second tubular shaft, a spider plate formation mounted for rotation about the stationary shaft, and pivot means for the pinion gear carried by the spider plate formation and means for period-

ically locking said spider plate against rotation for pre-determined increments of time.

5. The combination of claim 4 in which a friction device acts between the second tubular shaft and the stationary shaft to cause rotation of the spider plate except when restrained against rotation by said locking means. 5
